UNITED STATES PATENT OFFICE.

ARTHUR WM. SHIRL, OF MILWAUKEE, WISCONSIN.

AIRPLANE CONTROL

1,419,416.

Specification of Letters Patent. Patented June 13, 1922.

Application filed October 24, 1921. Serial No. 509,802.

To all whom it may concern:

Be it known that I, ARTHUR W. SHIRL, a citizen of the United States, residing at Milwaukee, in the county of Milwaukee and

5 State of Wisconsin, have invented new and useful Improvements in Airplane Controls, of which the following is a specification.

This invention relates to improvements in airplanes, an object of the invention being to 10 provide means whereby the fuselage will remain horizontal in rising and alighting so as to permit the ship to leave the ground after a short start and to facilitate landing.

Another object of the invention is to provide means whereby the ship will readily respond to the movements of the controls so 15 that the ship can be maneuvered in the minimum amount of space and time.

This invention also consists in certain other 20 features of construction and in the combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a plan view of a ship constructed in accordance with my invention.

Figure 2 is an elevation thereof.

Figure 3 is a fragmentary horizontal sectional view.

35 Figure 4 is a section on line 4—4 looking in the direction of the arrow.

Figure 5 is a similar section looking in the opposite direction, with parts broken away.

Figures 6 and 7 are detail views.

40 In these views the planes 1 and 2 are rockingly connected with the fuselage by means of the stationary shaft 3 to which the planes are pivotally connected. This shaft is rigidly supported by means of the braces 4 and

45 the body. A pair of shafts 5 and 6 are rotatably supported in the body and in the braces 4', said shafts having cranks 7 thereon which are slidingly connected with the planes or wings by means of the clips 8 en-

50 gaging the guides 9, secured to the rear edges of the planes. Thus as the shafts 5 and 6 are rocked, by means hereinafter described, the planes will be turned about the shaft 3 so that they can be moved to a position parallel with the longitudinal plane of

55 the body or at an angle to such plane. The

inner ends of the shafts 5 and 6 are rotatably connected together in any suitable manner so that one shaft can be rotated independently of the other.

60

The means for rotating the shafts 5 and 6 comprises a vertically arranged shaft 10, suitably journaled in the fuselage and adapted to be rotated by the feet of the pilot through means of the foot pedal 11, the segments 12 connected with said pedal and the cables 13 and chain 14 which connect the members 12 with the pinion 15 on said shaft 10. Thus the pilot or operator can turn the shaft 10 in either direction by means of his 70 feet.

Worm gears 16 and 17 are carried by shaft 10, the worm 16 meshing with the worm gear 18 loosely mounted at the junction of the shafts 5 and 6 and the worm 17 meshing with the gears 19 on the horizontal shafts 20 to which the pinions 21 are secured, said pinions meshing with the large gear 22 which is slidably mounted on shaft 23. This gear 22 is formed integral or is suitably connected 80 with the bevel gear 24 which engages the bevel gears 25 and 26 on the shafts 5 and 6 when the gears 22 and 24 are moved forwardly by the hand lever 27 which is connected with the grooved collar on the gear 22 85 by means of the forked rod 28. By moving said hand lever in an opposite direction the gear 24 will move out of mesh with the gears 25 and 26 though the gear 22 will remain in mesh with the pinions 21 due to the fact 90 that said pinions are of great width.

The gear 18 is provided with clutch teeth 29 at each side thereof which are adapted to be engaged by the teeth on the clutch parts 30 which are slidably mounted on the shafts 95 5 and 6 so that both or either shafts 5 and 6 can be connected with the gear 18, to be rotated thereby, whenever desired. These clutch parts are shifted by means of the rods 31 having their upper ends forked and 100 engaging the clutch parts and having their lower ends provided with arms 32 which are pivotally connected to the forked end of a rod 33 which has its other end passing through a bracket 34 on rod 28, a spring 35 105 being arranged between the bracket 34 and the enlarged end of said rod 33. These parts are so arranged that when the hand lever 27 is moved rearwardly the gear 24 will be moved out of mesh with the gears 25 and 26 110 and the clutch parts 30 moved into engagement with the teeth on the gear 18 so that

the shafts 5 and 6 will move in unison when the pedal 11 is actuated. When the lever 27 is moved in the opposite direction the gear 24 will be moved into engagement with the 5 gears 25 and 26 and the clutch parts will be moved out of engagement with the gear 18 so that the shafts 5 and 6 will be moved in opposite directions when the pedal is actuated. By moving the pedal in one direction 10 or the other the planes can be made to move in either direction.

I also provide a pair of stabilizers 36 and 37 at the tail end of the ship which are pivotally supported by the shaft 38. These 15 stabilizers are connected by the cables 39 with the pulleys 40 on the shafts 5 and 6 so that when said shafts 5 and 6 are rotated the stabilizers will be rocked upon their pivots. Thus the stabilizers will move in 20 unison with the planes 1 and 2. I also provide a large elevator 41 which is controlled thereto by the lever 42 which is connected thereto by the cables 43, and the rudder 44, also controlled by a suitable lever in the cock pit.

25 From the above it will be seen that the planes at the front of the machine and the stabilizers at the rear can be moved simultaneously in the same direction or one pair of planes and stabilizers can be moved in one 30 direction while the other pair is being moved in the opposite direction.

These movements of the various parts will permit the airplane to leave the ground after traveling a short distance as well as 35 facilitating landing. The ship can also be maneuvered very quickly and it can make sharp turns and in both ascending and descending the fuselage may remain in horizontal position. By placing the parts in 40 the neutral position the ship can be controlled in the ordinary manner by the rudder and elevator.

It is thought from the foregoing description that the advantages and novel features 45 of my invention will be readily apparent.

I desire it to be understood that I may make changes in the construction and in the combination and arrangement of the several parts, provided that such changes fall within 50 the scope of the appended claims.

What I claim is:—

1. In an airship, a plane at each side thereof supported to have movement about a horizontal axis, manually operated means 55 for imparting movement to the planes, manually operated means for causing such action to either move the planes simultane-

ously in the same direction or in reverse directions, a stabilizer at each side of the ship and means for connecting the same 60 with a plane so that the stabilizer will move with the plane.

2. In an airship, a plane at each side thereof supported for movement about a horizontal axis, a shaft connected with each 65 plane for moving the same, a gear, a pair of clutch means for connecting the same with the shafts, a gear on each shaft, a sliding gear adapted to engage therewith, means for moving the clutch means into engagement with the first mentioned gear and the sliding gear out of engagement with the gears on the shafts and vice versa, a drive shaft and gears connecting the same 70 with the clutch gear and the sliding gear. 75

3. In an airship, a plane at each side thereof supported for movement about a horizontal axis, a shaft connected with each plane for moving the same, a gear, a pair of clutch means for connecting the same 80 with the shafts, a gear on each shaft, a sliding gear adapted to engage therewith, means for moving the clutch means into engagement with the first mentioned gear and the sliding gear out of engagement with the gears on the shafts and vice versa, a drive shaft, gears connecting the same 85 with the clutch gear and the sliding gear and foot actuated means for rotating the drive shaft. 90

4. In an airship, a plane at each side thereof supported for movement about a horizontal axis, a shaft connected with each plane for moving the same, a gear, a pair of clutch means for connecting the same 95 with the shafts, a gear on each shaft, a sliding gear adapted to engage therewith, means for moving the clutch means into engagement with the first mentioned gear and the sliding gear out of engagement with the gears on the shafts and vice versa, a drive shaft, gears connecting the same 100 with the clutch gear and the sliding gear, foot actuated means for rotating the drive shaft, a stabilizer at each side of the ship adjacent the rear thereof, a pulley on each of the plane actuating shafts and cables connecting the stabilizers with the pulleys so that the stabilizers will be actuated simultaneously with the planes. 105

In testimony whereof I affix my signature.

ARTHUR WM. SHIRL.
